UNITED STATES PATENT OFFICE.

WILLIAM F. BEERY, OF NODAWAY MILLS, IOWA.

HANGING DOORS.

SPECIFICATION forming part of Letters Patent No. 234,703, dated November 23, 1880.

Application filed July 8, 1880. (No model.)

To all whom it may concern:

Be it known that I, W. F. BEERY, of Nodaway Mills, in the county of Page and State of Iowa, have invented certain new and useful 5 Improvements in Hanging Doors; and I do hereby declare that the following is a full, clear, and exact description of the invention, which will enable others skilled in the art to which it appertains to make and use the same, reference being had to the accompanying drawings, which form a part of this specification.

Figure 1 is a perspective view of a door having my improved attachment. Fig. 2 is a vertical sectional view. Fig. 3 is a horizontal 15 sectional view, and Figs. 4 and 5 are details.

Corresponding parts in the several figures are denoted by like letters of reference.

This invention relates to certain improvements in door-hanging devices, which will 20 be hereinafter fully described, and particularly pointed out in the claim.

In the drawings is the door-frame, the top and side of which are provided with recesses B C, in which are adjustable sliding pieces D 25 E, to the edge of which latter, E, the door F is hinged. The piece D is vertically adjustable in the recess B, where it is retained by means of two clamping-screws, G, passing through vertical slots H in said piece D. At 30 its inner end the said piece is provided with a slide, I, of sheet metal or other suitable material, adjustable by a set-screw, J, so as to be capable of being moved toward or away from the sliding piece E, to which the door is hinged, 35 and thus close any gap that might otherwise remain between the slides D and E.

The slide E is provided with two oblique slots, K K, faced by or lined with metallic plates provided with a row of teeth or cogs, L,

engaging pinions or semi-pinions M, formed 40 upon disks N, and sunk in suitable recesses in the jamb, as shown. The said disks N are provided with milled thumb-pieces S, by means of which they may be readily turned to adjust the slide E to any desired position. Through 45 a central perforation in the pinion, disk, and thumb-piece is passed a set-screw, O, which, when tightened, presses against the disk so as to prevent it and the pinions from revolving. At its lower end the sliding piece E is provided with a slide, P, adjustable against the carpet-strip by a set-screw, Q.

When in dry or wet weather the door shrinks or expands so as to cause it not to fit in the frame, the sliding pieces D E and the slides 55 upon the same may be easily and quickly adjusted to remedy the defect.

Having thus described my invention, I claim and desire to secure by Letters Patent of the United States—

The combination, with a door-frame, of the vertically-adjustable sliding piece D, having slide I and clamping-screws G, the laterally-adjustable sliding piece E, provided with slide P, and oblique slots K, having cogs L, and the 60 set-screw O, disk N, and pinion M, all constructed and arranged as shown and described, whereby the size of the door-opening is regulated so as to compensate for swelling or shrinking of the door, as set forth.

In testimony that I claim the foregoing as my own I have hereto affixed my signature in presence of two witnesses.

WILLIAM F. BEERY.
